AUTOMATIC CLAMSHELL BUCKET

Frank Caoli, Greenwich, Conn.

Application March 28, 1940, Serial No. 326,348

5 Claims. (Cl. 37—184)

This invention relates to buckets of the clam shell type, and has for an object to provide an improved and simplified construction which is automatic in operation to lock the bucket closed and retain it closed until released by the operator, and when dropped in the open position on to material to be raised or excavated and tension is placed on the lifting cable, the jaws will be automatically closed and locked in this position.

It is also an object to provide a bucket of this type which does not require an extra cable with its necessary complications of pulleys, etc. for opening and closing the bucket.

Another object is to provide a bucket of this type of simplified and improved construction which will be efficient and effective in operation, and which is not easily gotten out of order.

With the foregoing and other objects in view I have devised a construction as illustrated in the accompanying drawings forming a part of this specification. It will, however, be understood that various changes and modifications may be employed within the scope of the invention.

In these drawings:

Fig. 1 is a side elevation of a bucket involving my improved construction with the jaws in closed position and with certain parts broken away to more clearly show the construction;

Fig. 2 is a similar side view showing the jaws in the open position;

Fig. 3 is a view looking from the right of Fig. 1;

Fig. 4 is a transverse section substantially on line 4—4 of Fig. 2;

Fig. 5 is a section substantially on line 5—5 of Fig. 6;

Fig. 6 is a vertical central section looking from the left of Fig. 1 and on an enlarged scale; and

Fig. 7 is a section substantially on line 7—7 of Fig. 6.

The improved bucket construction shown is of the clam shell type comprising two jaws 10 each having upwardly extending arms 11 pivotally supported on bearings 12 on a supporting member 13. The jaws shown are of the closed or solid type, but it will be understood that I am not limited to the use of such jaws, but may use a rake arrangement or jaws having projecting studs or teeth at their lower inner edges. Located above the supporting member 13 is a block 15, and this block has a pair of pivot bearings 16 projecting from each end from which are suspended supporting links 17 pivoted at

5 their lower ends at 18 to the two jaws of the bucket, preferably at the inner sides of the end walls, and at points below and outwardly of the pivotal connections 12 of the arms of the jaws to the support 13.

Slidable in the block 15 is a hollow shaft 19 having at its lower end a rounded head 20 with a shoulder 21. The shaft also carries a collar or flange forming a shoulder 22, and embracing this 10 shaft is a coil spring 23 abutting at its opposite ends against the shoulder 22 and the block 15. This spring normally tends to force the shaft 19 downwardly and carry the head 20 toward the support 13, and under certain conditions to cause 15 it to interlock with a catch on this support, which will presently be described. Secured to the upper end of the shaft 19 is means for connecting thereto a lifting chain or cable 24. This in the present showing comprises an eye 25 mounted 20 in a block 26 which is in turn mounted in the upper end of the shaft 19 by any suitable means, such for example as screw threads or welding. To assist in keeping the parts in alignment and facilitate guiding action between the shaft 19 25 and block 15 and also to insure that the lower end of the shaft is brought into proper relation with the support 13, a second shaft 27 is slidable within the shaft 19 and connected at its lower end, as shown at 28, to the support 13.

20 The cooperating locking means on the support 13 for under certain conditions locking the shaft 19 to this support, comprises a slidable catch member 29 having a projecting extension 30 adapted to engage over the shoulder 21 on the shaft 19. It is slidable within the housing 31 and is normally held in the projected position by a spring 32. The rear end of the cavity in which the catch is mounted is open as indicated at 33 to prevent accumulation of dirt and dust within the cavity. Pivotated to this support 30 at 34 is a forked lever 35 carrying a transverse pin 36 extending through elongated longitudinal slots 37 in the opposite sides of the housing and vertical slots 38 in the side arms of the lever 35. It also projects through the catch 29 and serves as a means for connecting the catch to the lever and retracting this catch when the lever 35 is swung outwardly or to the right as shown in dotted lines Fig. 6. For operating this catch a flexible cord or light cable 39 may be connected to the lever 35 and carried to the operator in the cab or other position for operation of the bucket. The lifting cable 24 leads over the usual guide sheaves or pulleys on the boom to the winding drum in the lifting apparatus.

The operation is as follows:

When the jaws are filled and are being lifted they are closed as shown in Fig. 1. At this time strain is on the cable 24 and shaft 19, and the shoulder 21 at the lower end of this shaft is under the projecting end 30 of the catch 29 on the support 13 so that this shaft is locked to this support. The pull on the shaft 19 and on the support 13 raises this support and the pivots 12 carried thereby so as to swing the jaws about the pivots 18 and retain them in closed position. When the bucket has been raised and carried over the location where the material is to be dropped, as for instance in a truck, the operator pulls the cord 39 thus withdrawing the catch extension 30 from over the shoulder 21. The weight is so distributed that the support 13 and the pivots 12 immediately drop turning the jaws about the pivots 18 and thus separating the lower ends of the jaws or opening them and discharging the material held thereby. The jaws are now in the position of Fig. 2, and as the strain of the weight is still on the cable 24 and the shaft 19 this shaft is retained in its uppermost position and with the spring 23 compressed. The jaws are 25 then carried in this position back over the material to be excavated and dropped in this position down into this material. As the tension is removed from the cable 24 the spring 23 expands to move the shaft 19 downwardly to carry its head 20 and shoulder 21 toward the support 13 and carry the shoulder 21 under the projection 30 of the catch 29. To facilitate this action the outer surface of the head may be inclined or curved as shown, and the upper surface of the extension 30 may also be similarly shaped, so as to give the desired camming action to retract the catch 29 and to permit the head 20 to move past the extension 30 to the position shown in Fig. 6. Then as tension is placed on the cable 24 it draws the shaft 19 together with the support 13 and pivots 12 upwardly swinging the jaws inwardly about the pivots 18 and thus closing the jaws. At the same time it compresses the spring 23 to the position shown in the drawings preparatory to the next operation of shifting the shaft 19 when strain on the cable is released after dropping the open bucket into the material to be excavated. It will thus be seen that the jaws are automatically locked closed and remain so until the catch 29 is again released by pulling on the cord 39.

It will be also seen that this is a simple and effective mechanism which does not require a separate cable for opening and closing the jaws, but these are automatically closed by tension applied to the lifting cable and are automatically held closed until the interlocking connection between the shaft 19 and the support 13 is released.

Having thus set forth the nature of my invention, what I claim is:

1. In a device of the character described, a supporting member, a pair of bucket jaws pivoted to said member, a block above the supporting member, supporting links pivoted to the block and to said jaws below the pivots to said member, a shaft secured to said member and slid-

able in the block, a hollow shaft enclosing the first shaft and slideable in the block, a catch on the supporting member adapted to engage and hold said second shaft to hold the jaws in closed position, a spring tending to shift the hollow shaft to engage said catch, means for connecting a lifting cable to said hollow shaft to lift the jaws, and means for releasing said catch to permit the jaws to open.

2. In a device of the character described, a support having pivots, a pair of bucket jaws having arms hung on said pivots, a shaft secured to said support, a second shaft slideable on the first shaft and having a shoulder, a block slideable on the second shaft, links pivoted to the block and to said jaws, means for securing a lifting cable to the second shaft, a catch on the support adapted to engage said shoulder and by tension on the cable to move the jaws to closed position, a spring tending to move the second shaft to engage the catch, and means to release the catch to permit the jaws to open.

3. In a device of the character described, a support, a pair of bucket jaws pivotally mounted on said support, a shaft secured to the support, a second shaft slideable on the first shaft, means for connecting a lifting cable to the second shaft, a block in which the second shaft is slideable, supporting links pivoted to the block and to the jaws, a spring tending to move the second shaft toward the support, cooperating means on the latter shaft and the support to lock the shaft to the support so that tension on the cable will lift the support to close the jaws, and means for releasing the locking means to permit the jaws to open.

4. In a device of the character described, a support, a pair of bucket jaws having upwardly extending arms pivoted to the support, a block above the support, supporting links pivoted to the block and to the jaws below and outwardly of their pivots to the support, a hollow shaft extending through and slideable in the block, means for connecting a lifting cable to the shaft, a spring tending to move the shaft toward the support, cooperating means on the shaft and the support to lock the shaft to the support so that tension on the cable will lift the support to close the jaws, a second shaft secured to the support and guided for sliding movement in the first shaft, and means for releasing the locking means to permit the jaws to open.

5. In a device of the character described, a support, a pair of bucket jaws pivotally mounted on said support, a block, supporting links pivoted to the block and to the jaws, a hollow shaft extending through and slideable in said block, means for connecting a lifting cable to said shaft, a spring embracing the shaft and tending to shift the shaft toward said support, cooperating means on the shaft and the support to lock the shaft to the support so that tension on the cable will lift the support to close the jaws, a second shaft secured to the support and slideable in the first shaft, and means to release the locking means to permit the jaws to open.

FRANK CAOLI.
